UNITED STATES PATENT OFFICE.

JACOB D. MCKINNEY, OF HEMPHILL, TEXAS.

BURIAL-CASKET.

1,260,927.

Specification of Letters Patent. Patented Mar. 26, 1918.

Application filed September 15, 1916. Serial No. 120,355.

To all whom it may concern:

Be it known that I, JACOB D. MCKINNEY, a citizen of the United States, residing at Hemphill, in the county of Sabine and State of Texas, have invented certain new and useful Improvements in Burial-Caskets; and I hereby declare that the following is a full, clear, and exact description thereof, reference being had to the accompanying drawings, which form part of this specification.

This invention relates to a novel and improved burial casket or coffin and has for one of its aims the production of a casket constructed in a manner to obviate the necessity of the use of all metallic securing devices now commonly employed and which corrode and deteriorate from moisture and the salt of the body of the corpse when the ordinary casket has been deposited in the ground with the result that the parts constituting the usual form of casket become dismembered and fall apart and thereby expose the body of the corpse to the moisture and water in the ground as well as to attack by parasites and burrowing animals.

Another aim of this invention is to provide a non-destructible casket comprising a base and a removable body or casing therefor and between which may be interposed any suitable packing or cushioning material such as a pneumatic ring, pipes, felt, cotton waste, excelsior or other suitable packing material to prevent jarring of the casket and breakage thereof by sudden impact between the meeting edges of the casing and the base which may be occasioned during the transportation of the casket, but which packing material is preferably removed when the casket is to be deposited in the ground and for this purpose the base of the casket is provided with means for receiving a securing and sealing medium for efficiently cementing and sealing the casing upon the base to provide a tight joint between the meeting points of the casing and the base for effectually excluding moisture and germs from gaining access into the interior of the casket.

A further aim is to provide the casing or upper coffin body with handles or handle bars to facilitate the handling and placing of the casing upon the base of the casket and for removing the casing or upper coffin body from the base, and to provide the base of the casket with stirrups or straps provided with handles or handle bars for han-

dling the base member of the casket alone and to also handle the casket in its entirety, that is, to handle the base member together with the upper coffin body or casing thereon. 60 The base member of the casket is further provided with a surrounding band or hoop for reinforcing the base member and to provide a guide for the casing when placing the same upon the base member. The reinforcing member also forms part of the means for the reception of the sealing medium which secures the upper coffin body or casing upon the base member of the casket to thus form a unitary structure. 65

A further aim is the production of a burial casket having a base member formed of any suitable plastic material, wood, or fiber, preferably hard wood, and provided with an upper surface body of cement or the like, and an upper coffin body or casing formed preferably of suitable plastic material and formed with an open bottom, the top of the upper body being closed by the same material that the remaining portion is 70 formed, if desired, but I preferably form the top of the upper body or casing with a surrounding groove or recess and suitably secure therein a plate or pane of glass which may cover the entire upper portion of the 75 casing or the glass may cover any desired lesser portion.

I will explain the invention as illustrated in the accompanying drawings and summarize in the claims the combination of the 80 novel parts thereof for which I desire to secure protection.

In said drawings:

Figure 1 is a perspective view of the casket with its parts in assembled relation. 95

Fig. 2 is a vertical longitudinal sectional view.

Fig. 3 is a vertical transverse sectional view on line 3-3 of Fig. 1 showing the casket in condition for transportation with 100 the cushioning member interposed between its sections.

Fig. 4 is a similar view to Fig. 3 but showing the removal of the cushioning member and the sections cemented together preparatory for burial. 105

In said drawings, 1 denotes the base member or bottom of the sectional casket preferably provided with upwardly and outwardly inclined sides and ends and which 110 may be formed of any suitable material but I preferably employ hard wood and next

- to this any suitable fiber and may form in the surrounding upper edge of the base 1 the groove or rabbet 1^a, and the top of the base 1 is preferably covered with a top layer 5 of any suitable thickness of plastic or cementitious material 2 having its edges 2^a forming a coating for the side wall and bottom of the rabbet 1^a of the base member 1. Surrounding the sides and ends of the base 1 10 and of the same contour is the reinforcing band or hoop 3. This hoop is preferably a metallic hoop and is secured to the base 1 in any suitable manner but preferably swelled thereon by first heating the same and then 15 allowing it to contract and impinge the edges of the base 1 and may be further secured to the base 1 by the nails 1^b or other securing means. The band or hoop 3 is preferably formed wider than the thickness of 20 the base member 1 and its surface coating 2 so that the upper edge of the hoop 3 will project slightly above the plane of the upper surface of the coating 2. The hoop 3 extends in an upwardly and outwardly direction 25 with the upper longitudinal half forming one side wall of the surrounding recess of which the rabbeted portion or groove 1^a provides the bottom and other side wall of the recess. 30 Suitably secured upon the under side of the base 1 are a plurality of straps or stirrups 4, preferably two as shown, and these stirrups 4 have their ends provided with the upstanding arms 4^a, in the upper ends of 35 which are provided the eyes or loops 4^b having suitably secured therethrough the handle bars 4^c, though individual handles may be secured to the eyes or loops 4^b of the stirrups 4 if desired, the stirrups 4 being 40 preferably secured upon the base 1 by the nails 4^d or other suitable securing means.
- Adapted to be supported by and secured upon the base 1 is the casing or upper coffin body 5 formed of any suitable plastic, 45 fibrous, or cementitious material and constructed with an open bottom and preferably upwardly converging side and end walls. The top of the body 5 is also preferably open and has an opening in its upper 50 side covered by a plate or pane of glass 5^b which may be secured therein in any suitable manner, as by sealing medium 5^c. Upon the outer surfaces of the side walls of the body 5 are the lugs or ears 5^a provided with the openings 5^e therethrough and extending through the openings 5^e of 55 the lugs 5^a and suitably secured therein are the handle bars 5^f, though there may be individual handles secured to the lugs 5^a if desired in lieu of the handle bars 5^f. Upon 60 the lower bottom edge of the casing 5 is preferably formed the outwardly extending rib or flange 5^g, the purpose and function of which will be hereinafter explained, and within the lower edge portion of the casing

5 may be embedded any suitable form of reinforcing material to strengthen its edges.

When using the casket the upper coffin body or casing 5 is removed from the base 1 and the corpse is positioned upon the base 1, and if the casket is to be shipped or otherwise transported the casing 5 is then placed over the corpse and upon the base 1, but preferably previously to the placing of the casing 5 a suitable packing material or substance is placed within the recess 1^a beneath the lower edges of the casing 5 and which packing material may be in the nature of the pneumatic ring 6 shown in Figs. 2-3 or tubular hose members may be employed 80 and if desired felt, cotton waste, excelsior, or any other suitable packing material may be used in lieu of the pneumatic ring 6; and as a precautionary measure the upper coffin body or casing 5 may be temporarily 85 locked or secured upon the base 1 in any suitable and desirable manner, for instance, the handle bars 4^c of the base member 1 and the handle bars 5^f of the casing 5 may be locked together by any suitable means 90 such as straps and padlocks, locked chains or seals, and there may be interposed between the lower portion of the casing 5 and the upper portion of the hoop 3 the strips 7 to prevent lateral and endwise movements 95 of the casing 5.

When the casket has reached its destination or place of burial, strips 7 and the casing 5 are removed from the base 1 and afterward the packing 6, or whatever other non permanent packing material has been employed, is withdrawn from within the recess 1^a. The casing 5 is replaced upon the base member 1 with its lower edges snugly seated therein and afterward a suitable cementitious or bituminous material 8, see Fig. 4, is poured into the recess 1^a which is formed by the rabbeted portions of the base 1 and the reinforcing hoop or band 3, the cementitious material securely cements the 110 lower edge portion of the upper coffin body or casing 5 to the portion 2^a of the surface 2 upon the base member 1, this cementitious material 8 by engaging the rib or flange 5^g of the casing 5 more efficiently secures the 115 casing 5 upon the base member 1 and thus forms a unitary structure which will prevent moisture, water and parasites from gaining access into the interior of the coffin body when the casket has been deposited in 120 the grave.

The top of the coffin body 5 may be made of the same material as the sides and ends and formed integral therewith, or the glass top 5^b may extend the full length and width 125 of the top of the body 5 as shown or may be made in any desired form and dimension and constructing the opening in the top of the body 5 in accordance with the size and shape of the pane of glass to be used. 130

The coffin body or casing 5 and the upper surface 2 of the base 1 are preferably formed of plastic, cementitious or argillaceous substances and when secured together by the 5 sealing medium 8 these parts form an integral structure having no securing screws or bolts to decay and allow the parts to fall apart and thereby expose the corpse to the influence of moisture and water and attacks 10 by parasites, burrowing animals and the like. Furthermore, I provide a sectional casket whereby the corpse may be more readily positioned within the casket by the provision of the base 1 and the removable 15 cover or casing 5, the casket being capable of shipment without the danger of breakage or displacements and which can be readily handled either as a whole or in part.

As stated the casing and base, if desired, 20 may be made of any suitable material. Where very light caskets are desired they might be made of thin sheet metal or of paper. If made of paper it should be treated to render same moisture and acid 25 proof. If made of sheet metal they should be provided with a moisture and acid proof coating or lined with treated paper. Such light casings could be nested for transportation. If the bases were made of similar 30 light material with integral side flanges they could also be nested. The casings and bases would fit or telescope substantially as indicated in Figs. 3 and 4, and the joint therebetween could be sealed by suitable 35 cementitious material; such joint between the casing and the base may be made at different points in the total height of the casket according to the depth of the flange on the base and sides of the casing.

40 The casket may be padded and lined in any suitable manner, and while I prefer to form the parts thereof of the materials and shapes above set forth, the base and casing or either may be formed of any indestructible, 45 non-corrosive and impervious material or materials and of any desired conformation, and further, my invention is not to be understood as being restricted to the exact construction shown and described as any desired and expedient alterations and variations 50 therein may be resorted to without departing from the spirit of the invention or the scope of the claims.

What I claim is:

55 1. In a casket, the combination of a base member having a surrounding groove, a reinforcing hoop or band encompassing said base member and groove and forming an exterior enlargement of the outer wall of the 60 groove, a hollow casing adapted to be positioned upon said base member within said groove and hoop, and means for securing said casing within the groove of said base member.

65 2. In a casket, the combination with a

base member having a surrounding groove formed in its upper edges, a body upon said base member, a reinforcing band surrounding said base member and providing a channel with said groove, a casing adapted to be seated in said channel, an adhesive material introduced in said channel, and a rib or flange upon said casing engaged by the adhesive material.

3. In a casket, the combination with a 75 base member having a surrounding groove formed in its upper edges, a body upon said base member and said groove, a reinforcing band surrounding said base member and providing a channel with said groove, an 80 inverted hollow casing adapted to be positioned upon said base member with its lower edges seated in said channel, an adhesive material introduced in said channel and engaging the lower edges of said casing, and 85 an outwardly projecting rib or flange upon the lower edges of said casing engaged by the adhesive material.

4. In a casket, the combination of a base having a groove formed in its upper edges, 90 a reinforcing band or hoop surrounding said base member and having its upper edges lying above the plane of said base member, handle securing means upon said base member, handle bars secured to said 95 handle securing means, and a casing adapted to be secured upon said base member within said groove and band.

5. In a casket, the combination of a base having a groove formed in its upper edges, 100 a reinforcing band or hoop surrounding said base member and having its upper edges lying above the plane of said base member, handle securing means upon said base member, handle bars secured to said handle securing means, a casing adapted to be secured upon said base member within said groove and band; and handle bars upon 105 said casing.

6. In a casket, the combination of a base 110 having a groove formed in its upper edges, a cement body upon the upper surface of said base member and said groove, a reinforcing band or hoop surrounding said base member and having its upper edges lying 115 above the plane of said cement body upon said base member, a plurality of stirrups secured upon the under side of said base member, and handle bars secured in the upper ends of said stirrups.

7. In a casket, the combination of a base having a groove formed in its upper edges, a cement body upon the upper surface of said base member and said groove, a reinforcing band or hoop surrounding said base 125 member and having its upper edges lying above the plane of said cement body upon said base member, a plurality of stirrups secured upon the under side of said base member, and handle bars secured in the upper

ends of said stirrups, with an inverted hollow casing adapted to be secured upon said base member and provided with handle bars.

8. In a casket, the combination of a base member having its upper edges rabbeted, a band surrounding said base member and its rabbeted portion, said rabbeted portion and the upper portion of said band providing a channel, a casing seated within said channel, a flange upon the lower edges of said casing, and a cementitious body introduced in the said channel and around the edges of said casing and the flange thereof for securing said casing upon said base member.
- 15 9. In a casket, the combination of a base member having its upper edges rabbeted, a reinforcing hoop or band surrounding said base member and its rabbeted portion, said rabbeted portion and the upper portion of said reinforcing band providing a channel, an inverted hollow casing having its lower edges seated within said channel, an outwardly projecting rib or flange upon the lower edges of said casing, a cementitious body introduced in the said channel and around the edges of said casing and the rib or flange thereon for securing said casing upon said base member, and means for handling said base member together with said casing.
- 30 10. A base member, comprising a body portion having its side and end walls upwardly and outwardly inclined, a reinforcing band surrounding said body portion and of the contour of the side and end walls of the body portion, a top layer upon said body portion, bars upon the under side of said body portion, arms upon the ends of said bars, loop members upon the extremities of said arms, and handle bars secured in said loop members to provide means for carrying said base member.
- 35 11. A base member, comprising a body portion having its upper edges rabbeted, and its side and end walls upwardly and outwardly inclined, a reinforcing band sur-

rounding said body portion and of the contour of the side and end walls of the body portion, said rabbeted portion and said band forming a channel, a top layer upon said body portion and said channel, horizontal bars upon the under side of said body portion, upstanding angle arms upon the ends of said horizontal bars, loop members upon the extremities of said angle arms, and handle bars secured in said loop members to provide means for carrying said base member.

12. A burial casket comprising a base; a casing closed at top and sides but open at bottom and having projecting ribs on its sides, said casing being adapted to be seated on the base to protect and cover a body laid upon the base; longitudinal handle-rods transfixing ribs on said casing whereby it may be moved independently of the base; and handles attached to the sides of the base whereby it may be moved independently of the casing or together with the casing when the latter is placed thereon, substantially as described.

13. A burial casket comprising a base provided with a channel adjacent its edge; a casing closed at top and sides but open at bottom and adapted to have its lower edge seated in said channel when placed upon the base; means for sealing the edge of said casing within said channel when the casing is placed on the base; longitudinally disposed handles on the sides of said casing whereby it may be moved independently of the base; transversely disposed angle arms attached to and extending under the base; and handle bars secured to said angle arms at opposite sides of the base for transporting the base either separately or together with the casing when the latter is placed on the base, substantially as described.

In testimony that I claim the foregoing as my own, I affix my signature.

JACOB D. MCKINNEY.
